(57) **CLAIM**

The ornamental design for the garment with an integrated gait belt, as shown and described.

DESCRIPTION

FIG. 1 is perspective view of the garment with an integrated gait belt; and

FIG. 2 is a rear perspective view thereof; and

FIG. 3 is a front elevation view thereof; and

FIG. 4 is a rear elevation view thereof; and

FIG. 5 is a left side view thereof; and

FIG. 6 is a right side view thereof; and,

FIG. 7 is a front perspective view thereof wherein the present invention is engaged with a user.

The broken lines depicting a garment, stitching and a user represent environment that forms no part of the claimed design.
